UNITED STATES PATENT OFFICE.

LINZY HICKS, OF OMAHA, NEBRASKA, ASSIGNOR TO HICKS RETINNING COMPANY, OF OMAHA, NEBRASKA, A CORPORATION OF NEBRASKA.

HEAT-INSULATED CONTAINER.

1,289,456.

Specification of Letters Patent. Patented Dec. 31, 1918.

Application filed April 20, 1916. Serial No. 92,403.

To all whom it may concern:

Be it known that I, LINZY HICKS, a citizen of the United States, residing at Omaha, in the county of Douglas and State of Nebraska, have invented certain new and useful Improvements in Heat-Insulated Containers; and I do hereby declare the following to be a full, clear, and exact description of the invention, such as will enable others skilled in the art to which it appertains to make and use the same.

This invention relates to improvements in heat insulating containers of the type adapted either for containing cold substances and retaining them at their low temperature, or for containing hot substances and retaining them at their high temperatures.

The primary object in view is the production of a simple and efficient structure adapted to provide in an inexpensive manner, a container of maximum efficiency in the non-conduction of heat.

With this and further objects in view, as will in part hereinafter become apparent and in part be stated, the invention comprises certain novel constructions, combinations and arrangements of parts as subsequently specified and claimed.

In the accompanying drawing:—

Figure 1 is a longitudinal vertical central section of a container embodying the features of the present invention, parts being seen in elevation.

Fig. 2 is a top plan view thereof.

Fig. 3 is an enlarged fragmentary side elevation observed from the plane at right angles to the plane of the section of Fig. 1.

Fig. 4 is a fragmentary section similar to Fig. 1 of a slightly modified embodiment, parts being seen in elevation.

Referring to the drawing by numerals, 1 indicates a container or receptacle, preferably of sheet metal and of any appropriate contour, but preferably cylindrical, with its upper end open and its lower end closed. The upper edge portion of receptacle 1 is turned downward to form an outstanding horizontal flange 2, having its outer portion resting upon a similar flange 3 formed at the upper edge of a casing 4, which casing is similar in contour to receptacle 1, but is sufficiently larger than the receptacle to surround and inclose all parts thereof except the upper end and be spaced therefrom.

The space between the casing 4 and the receptacle 1 is preferably filled with asbestos or other heat insulating means indicated at 5. The outer portion of the flange 3 is turned upward and produces an annular band or retainer 6.

The annular band 6 supports and is inclosed by a heat insulating fabric 7, such as a sheet of asbestos, and the outer face of the sheet is snugly engaged by an exterior casing 8, which conforms generally in contour to that of casing 4, and surrounds and incloses the same, except at the upper end, the casing 8 being sufficiently larger than casing 4 to leave a space 9 therebetween, which is preferably maintained as a vacuum space. The upper portion of the casing 8 is turned inward and bent downward to form an inclosed annular band 10, lapping past and lying within the inclosure 70 of the band 6. It is to be observed that the insulating sheet 7 is interposed between and in fact clamped between the bands 10 and 6, as well as lying between the band 6 and the inner surface of casing 8. The sheet 80 of insulation 7 extends a sufficient distance below the flange 3 to cover an inwardly extending bead 11, formed in any appropriate manner as by the crimping of the material of casing 8 to form an annular shoulder 85 underlapping the outer edge of flange 3 and sustaining the same and engaged parts against descending within the casing 1 either from the pressure of air incident to the vacuum space or from contained weight. 90

The upper face of the flange 2 forms an annular seat for a cover block 12 for the receptacle 1, the said block being preferably formed of wood or other like power conductor of heat. The block 12 is of sufficient 95 thickness to have its upper surface to lie above the uppermost portion of casing 8 when block 12 rests on the flange 2. The upper portion of casing 8 presents a rolled or rounded edge 13, on which rests a gasket 14, which is engaged by the outer edge portion of a preferably sheet metal cap 15 fixed to the upper face of the block 12. Cap 15 is preferably provided with a depending annular flange at its outer edge inclosing the 100 gasket 14. A recess or depression 16 is formed in the cap 15 and is engaged by a cam 17 carried by a cross rod 18 and having an operating handle 19 of sufficient length and relative location to lie on top of the cap 110

15 and hold the same in locked position as clearly indicated in Fig. 3. The shaft or rod 18 is rotatably mounted in open eyes 19' formed in ears 20, fixed to and up-
5 standing from the casing 8. The ears 20 are also preferably engaged by a bail 21 for facilitating carrying of the entire container.

The vacuum may be initially produced in
10 the space 9 in any known and appropriate manner, and one convenient method of such production consists of the provision of a soft metal nipple 22, communicating with the space 9 preferably through the bottom
15 of casing 8 and adapted to receive the hose of a vacuum pump. After the pump has been manipulated for producing as nearly perfect vacuum as possible, the nipple 22 has its walls mashed together and then bent
20 over to prevent intaking of air. A protecting housing 23 having a cap 24 is provided and surrounds the nipple 22.

It should be apparent from the foregoing that every precaution is taken in the structure disclosed to avoid distribution of heat by diffusion and the arrangement is also such as to largely prevent heat radiation. The operation of the structure is also obvious and consists briefly in elevating the handle or lever 19 until the cam 17 is lifted out of the recess 16 and then the rod 18 is withdrawn from the eyes 19' and the cap 15, with the cover block 12, may be then lifted from the receptacle. The substance
30 to be preserved, as for example, ice cream, is introduced and the parts are replaced. The heat of surrounding atmosphere, failing to find its way into the receptacle 1, will not affect the condition of the ice cream
35 for a prolonged period. When it is desired to remove the ice cream, the lock made up of cam 17 and coöperating parts is disconnected and the cover plate removed.

In Fig. 4 is illustrated a slightly modified embodiment wherein, in lieu of providing a special joint between the inner and outer casings, the several parts are anchored to a connecting ring. In this figure, the receptacle 1' is provided with a flange 2' overlapping flange 3' of casing 4'. The two flanges 2' and 3' are connected in any appropriate manner as by screws, with a supporting ring 7' of wood or other like power conductor of heat. The outer casing 8' is provided with a bead 11' underlapping the ring 7' and supporting the same in position. The inner surface of the ring 11' is preferably tapered downward and a block 12' is fitted within the taper so as to have its upper surface flush with the upper surface of the ring. A preferably metallic ring 15' is fixed to the upper surface of block 12' and outstands from the outer edge thereof and forms a flange overlapping the ring 7'.
65 A cross-web 16' is preferably formed inte-

gral with ring 15' for receiving the locking cam 17' having the same coöperating parts as has the cam 17 of the structure above described. The operation of the parts seen in Fig. 4 it is believed will be obvious from 70 the foregoing description.

What I claim is:—

1. A heat insulating container, comprising a casing, insulating means sustained at the upper portion of the casing, a container 75 within the casing sustained by and pendent from the insulating means and spaced from the casing, a heat non-conducting block removably closing the upper end of the receptacle, and means for detachably locking the 80 block in position against the container to bind the latter against the insulating means.

2. In a heat insulating container, the combination of an outer casing having an inwardly extending support, an inner casing 85 spaced from the outer casing, a suspending member carried by the inner casing and adapted to engage said support, a cover for the container fitting against the suspending member, and means carried by the outer casing for binding engagement against the cover to hold the said suspending member against the support.

3. A heat insulating container, comprising an inner casing, an outer casing spaced 95 from and surrounding the inner casing, a flange outstanding from the inner casing toward the outer casing and being formed adjacent the outer casing into an upstanding ring, means of support extending from the outer casing beneath the portion of the flange, and heat insulating means interposed 100 between the support and flange including the ring portion of the flange.

4. A heat insulating container, comprising an inner casing, an outer casing spaced from and surrounding the inner casing, a flange outstanding from the inner casing toward the outer casing and being formed adjacent the outer casing into an upstanding ring, means of support extending from the outer casing beneath the portion of the flange, heat insulating means interposed 110 between the support and flange including the ring portion of the flange, and a receptacle 115 arranged within and spaced from the inner casing and having means of support resting on a portion of the inner casing.

5. A heat insulating container, comprising an inner casing, an outer casing spaced 120 from and surrounding the inner casing, a flange outstanding from the inner casing toward the outer casing and being formed adjacent the outer casing into an upstanding ring, means of support extending from the outer casing beneath the portion of the flange, heat insulating means interposed 125 between the support and flange including the ring portion of the flange, and a receptacle arranged within and spaced from the inner 130

- casing and having a flange overlapping the flange of the inner casing.
6. A heat insulating container, comprising an inner casing, an outer casing spaced from and surrounding the inner casing, a flange outstanding from the inner casing toward the outer casing and being formed adjacent the outer casing into an upstanding ring, means of support extending from the outer casing beneath the portion of the flange, heat insulating means interposed between the support and flange including the ring portion of the flange, a receptacle ar-

ranged within and spaced from the inner casing and having a flange overlapping the flange of the inner casing, the upper end of the receptacle being open, and a heat insulating block resting upon the flange of the receptacle when closing the upper end of the receptacle.

In testimony whereof I affix my signature in presence of two witnesses.

LINZY HICKS.
